UNITED STATES PATENT OFFICE.

MAX POMERANZ, OF ASTORIA, NEW YORK.

BAG.

Application filed January 18, 1926. Serial No. 81,922.

This invention relates to new and useful improvements in bags and its object is to provide a bag which is particularly designed for use by bathers in carrying bathing suits and like articles. Heretofore in the production of bags of such a nature, much difficulty has been experienced in preventing the tearing of the material when forcing the articles to be carried, into the bag. Such obstacles are due largely to the nature of the material from which the bags are produced or more likely to the treatment to which the cloth, from which such bags are made, is subjected. It is customary in the manufacture of such articles to make them out of a water proofed fabric such as rubberized cloth and when sewn or riveted this cloth tears easily and as a consequence the rivets pull out or the bag splits with the result that in a short time the bag is wholly worthless. Furthermore, the bag handles which are ordinarily formed by sewing or otherwise securing separate pieces of material to the body of the bag are prone to tearing loose and it is one of the objects of the present invention to provide a bag wherein the handles are formed integrally with the body portion so as to do away with this difficulty. Another object of the invention is to provide a bag, the side walls and handles of which are formed of one continuous piece of material, thus providing in one sense a sling into which the articles to be transported are deposited. A further object of this invention is to provide the handle portions with a stiffening and reinforcing strip and to provide a metallic grip portion which is crimped over the edges of the material from which the bag is made to produce a smooth walled opening through which the hand is thrust when the bag is being carried. With the above and other objects in view, which will become more apparent as the description proceeds, the invention consists in the novel construction, combination and arrangement of parts which will be fully set forth in the following specification, claimed, and illustrated in the accompanying drawing, in which:

Figure 1, is a perspective view of a bathing bag, constructed in accordance with this invention;

Figure 2, is a longitudinal sectional view

on an enlarged scale, taken on line 2—2 of Figure 1;

Figure 3, is a fragmentary sectional view taken on line 3—3 of Figure 1; and

Figure 4, is a perspective view of a shopping bag constructed in accordance with this invention.

Referring to the drawing in detail, the numeral 10 designates a continuous strip of water proof material, such as rubberized cloth, which forms the side walls 11 and 12 and the bottom 13 of a bathing bag. Sewn to the marginal edges of the strip 10 are strips of similar material forming the end walls 14. The seams thus formed are bound with a suitable binding 15 and each end wall 14 is formed with a flap 16 at its upper end to partially close the upper end of the bag. Portions of a snap fastener 17 are carried by each flap so that the two flaps may be detachably secured together at their meeting edges and wholly cover the contents of the bag.

As illustrated, the upper ends of the strip 10 project beyond the upper ends of the walls 14 to provide handle portions 18 and 19, sewn or otherwise secured to the inner faces of each of the handle portions a lining strip 19. Thus it will be seen that a pocket is provided between each handle portion and its lining for the reception of a reinforcing and stiffening member 20.

As shown each handle portion, its lining and reinforcing member is pierced by an opening of a size to readily accommodate the fingers of the user and seated in each opening thus provided is a binding element such as a metallic flanged oval 21 which is crimped over the handle portion and lining, thus providing a smooth and convenient grip by which the bag may be conveniently carried.

It is to be understood that all raw edges of the material are neatly bound in order to overcome any tendency toward fraying.

In order to further strengthen the bag and prevent its tearing or ripping when inserting the articles to be carried, the rivets 22 are used across the corners as illustrated in Figure 3.

In the modified form of bag shown in Figure 4, it will be understood that like the bag previously described, the front and back walls 23 and 24 and the bottom are formed of one continuous piece of material

2
to which the end walls 25 are suitably attached, and that the handles 26 follow the construction previously described in detail. In order to more evenly distribute the load 5 throughout the entire length of the bag, reinforcing strips 27, such as strips of wood or steel, may be secured, between the body fabric and the lining as shown in dotted lines in Figure 4.

10 While in the foregoing there has been shown and described the preferred embodiment of this invention, it is to be understood that minor changes in the details of construction, combination and arrangement of 15 parts may be resorted to without departing from the spirit and scope of the invention as claimed.

What is claimed is:

1. As a new article of manufacture, a bag 20 comprising a bottom, side walls formed integrally with said bottom, end walls attached to the side walls and said bottom, handles formed integrally with said side walls, and flaps on said end walls to extend intermediate 25 said side walls.

2. A bag comprising a bottom, a pair of side walls formed integrally with the bottom, end walls secured to the edges of the side walls and bottom, flaps at the upper 30 ends of the end walls, means to connect the meeting edges of the flaps to provide a bag cover, handles extending upwardly from the upper ends of the sides, a lining for each

handle, and a reinforcing strip between each handle and its respective lining.

3. A bag comprising a bottom, a pair of side walls formed integrally with the bottom, end walls secured to the edges of the side walls and bottom, flaps at the upper 35 ends of the end walls, means to connect the meeting edges of the flaps to provide a bag cover, handles extending upwardly from the upper ends of the sides, a lining for each handle, a reinforcing strip between each handle and its respective lining strip, the 40 handles, linings and reinforcing strips being pierced, and a metallic binding entering each handle and clamping the same and its associated elements together.

4. A bag comprising a bottom, a pair of side walls formed integrally with the bottom, end walls secured to the edges of the side walls and bottom, flaps at the upper 45 ends of the end walls, means to connect the meeting edges of the flaps to provide a bag cover, handles extending upwardly from the upper ends of the sides, a lining for each handle, a reinforcing strip between each handle and its respective lining, and rivets connecting the side and end walls adjacent their upper 50 ends to reinforce the same and prevent the seams from ripping out.

Signed at New York, county of New York, State of New York, this 14th day of January, 1926.

MAX POMERANZ.
